UNITED STATES PATENT OFFICE.

WALTER T. LEE AND NORMAN MELLOR, OF PHILADELPHIA,
PENNSYLVANIA.

JOURNAL-BEARING.

SPECIFICATION forming part of Letters Patent No. 655,633, dated August 7, 1900.

Application filed March 10, 1900. Serial No. 8,167. (No model.)

To all whom it may concern:

Be it known that we, WALTER T. LEE and NORMAN MELLOR, citizens of the United States, and residents of Philadelphia, Pennsylvania, have invented certain Improvements in Journal-Bearings, of which the following is a specification.

The object of our invention is to so construct a bearing for the journals of rollers or pulleys such as are used in spinning and like machines as to provide for the secure retention of the roller or pulley in place when in use, but permit of the ready removal of the roller-journals from their bearings when necessary. This object we attain in the manner hereinafter set forth, reference being had to the accompanying drawings, in which—

Figure 1 is a plan or top view of a journal-bearing constructed in accordance with our invention, illustrating its application to a form of pulley or roller carrier common in spinning and winding machinery and showing one of the journal-retaining caps in its normal position and the other swung back out of the way. Fig. 2 is a transverse section, also showing one of the journal-retaining caps in position and the other swung back. Fig. 3 is a section on the line *aa*, Fig. 1. Fig. 4 is a view similar to Fig. 3, but illustrating a slight modification of the invention. Fig. 5 is a view, partly in elevation and partly in transverse section, illustrating another embodiment of our invention; and Fig. 6 is a transverse section on the line *ff*, Fig. 5.

In Fig. 1 we have shown at 1 a form of forked hanger or yoke common in spinning and winding machinery, the opposite legs of this yoke having boxes 2 for the journals 3 of a roller, pulley, or other element of the machine, the element shown at 4 being a roller, although the invention is equally applicable to bearings for the journals of a belt-drum.

The journals 3 are adapted to bushings 5, which are preferably of specially-prepared wood or other material which does not require lubrication; these bushings by preference fitting snugly into the boxes 2, so as to be prevented from turning therein, the journals turning in the bushings, although in

some instances the reverse may be the case—that is to say, the bushings may fit snugly to the journals and may turn in the bearings.

The bushings can be introduced into and withdrawn vertically from the bearings, so that the roller 4, after having the bushings 5 applied to its journals, can be readily dropped into or lifted out of place or the bushings may be slipped laterally onto the journals 60 after the latter have been introduced into the boxes.

Each of the bushings is normally held in position in its box by means of a swinging cap 9, which has a pivot-stem 10 passing through 65 an opening in a lug 11 on the box and having at its lower end a suitable head or enlargement, upon which acts a coiled spring 12, interposed between said head and the lug and tending to press the stem and likewise the cap 70 9 downward, so as to prevent accidental rise of the cap, although the weight of the cap and the fact that the pivot-stem is not centrally disposed may be relied upon to prevent such rise in some cases, as rising movement of the outer 75 portion of the cap would tend to jam the pivot-stem in the opening in the lug 11 of the box. Each cap has at the outer end a depending plate 13 for bearing against the end of the box 2 and preventing any lateral outward movement of the bushing 5, and each cap also has a portion 14, which enters the top of the box and engages with the front and back portions of the same, as shown in Fig. 3. When the caps are in their normal position, therefore, 80 85 they securely retain the bushings in the boxes both vertically and laterally, and in order to release either bushing it is necessary to first lift the caps until the depending portions 14 of the same are free from engagement with 90 the front and back portions of the boxes, the caps being then free to be swung around on their pivot-stems 10 to the position shown at the right-hand side of Fig. 1 and also at the right-hand side of Fig. 2, so as to uncover 95 the boxes and permit of the lifting of the roller 4 and its journal-bushings out of the boxes.

When either of the caps 9 is swung around out of retaining position, the pivoting-heel 9a 100 of the cap rests upon a rib 15 on one of the legs of the yoke and is thus supported in po-

sition to be again swung back over the box, downward pressure of the spring 12 upon the stem of the cap causing such friction between the under side of the cap and the top of the 5 rib as to effectually prevent the shaking or other accidental movement of the cap from its retracted position. It will be evident, however, that the lug 11 of the bearing might be such that the portions 14 of the cap would 10 bear upon the same when the cap was swung around to the open position, and it is equally evident that the contact of the heel 9^a and rib 15 or equivalent construction may be relied upon in place of shoulders 14 on the cap to 15 render necessary the lifting of the cap before it can be swung around. This necessity of lifting the cap before it can be moved out of retaining position precludes a possibility of the accidental shifting of the cap from such 20 retaining position.

Where the roller or pulley 4 is not subjected to any upward strain, a slotted bushing—such, for instance, as that shown at 5^a in Fig. 4—may be employed, this bushing being secured within the box 2 in any appropriate manner and the journals 3 of the roller or pulley 4 being dropped into or lifted from the slotted portion of the bushing when the caps 9 have been swung around out of the 30 way.

In Figs. 5 and 6 we have shown a further embodiment of our invention, the bushings 5 in this case being fitted to segmental transverse openings or recesses in the boxes 2^a, so 35 as to be readily insertible laterally into or removable laterally from said openings, although preferably they fit so snugly therein that they are not free to turn, the journals 3 turning in the bushings.

40 Slots 6 extend from the tops of the segmental openings which receive the bushings 5 up to the tops of the boxes 2^a, these slots being less in width than the diameter of the bushings, but equaling or exceeding in width 45 the diameter of the journals 3.

The boxes 2^a are recessed at top and bottom for the reception of an elastic retaining clip or cap 7, which consists, preferably, of a piece of elastic sheet metal bent so as to embrace the outer side, top, and bottom of each 50 box, said cap having lugs 8, which overlap the inner side of the box, as shown at the left-hand side of Fig. 5. Hence when these caps are in place the journals of the roller or pulley are properly held in their bearings, since the bushings 5 can only be drawn outward laterally from the openings in the boxes 2^a, and such lateral withdrawal of the bushings is necessary before the journals 3 can 55 be lifted from the boxes through the slots 6 in the top of the latter. Lugs on the boxes for engagement with openings in the cap 7 may, if desired, be employed instead of the reverse construction shown.

60 65 When it is desired to remove the roller or pulley, the spring-caps are slipped off, as shown at the right-hand side of Fig. 5, the

bushings 5 are withdrawn laterally, and the roller or pulley is then removed vertically, reapplication of the parts being effected by 70 a reversal of these operations.

Each of the caps 7 may, if desired, have but a single retaining lug or shoulder 8 to prevent accidental displacement, and in like manner the caps 9 may each have but a single retaining-shoulder, the double shoulder being preferred, however, in all cases.

If the boxes 2 are closed at their outer ends or other provision is made for holding the journals or bushings against lateral movement, the provision of the end plates 13 upon the caps 9 will be unnecessary, said caps simply confining the bushings 5 vertically in the boxes, as vertical removal of the bushings in this case would be the only permissible one, 85 and if the boxes 2 are contracted at the top, so as to vertically confine the bushings, or, in other words, are made as shown at 2^a, the swinging caps 9 may be provided with end plates 13, but need not necessarily extend across 90 the top of each box, any desired portion of the cap engaging with a shoulder on the bearing, or vice versa, in order to compel the lifting of the cap before it can be swung around. Each cap by preference, however, completely 95 covers the top of the box, so as to prevent, as far as possible, the access of dust and dirt to the bushing and journal of the roller.

Our invention is also applicable to bearings in which the journals are not provided 100 with bushings—for instance, to a bearing in which the journals are seated directly in the boxes and are prevented from being lifted therefrom by the removable caps or covers.

Having thus described our invention, we 105 claim and desire to secure by Letters Patent—

1. The combination of the journal-box with a retaining-cap therefor having a portion for closing the box so as to prevent removal of 110 the journal therefrom, said cap being movable in one direction to release the journal, but having a portion engaging with the box or its carrier and necessitating movement of 115 said engaging part in a different direction before the cap can be moved out of retaining position, substantially as specified.

2. The combination of the journal-box with a retaining-cap therefor having a portion for closing the box so as to prevent removal of 120 the journal therefrom, said cap being movable in one direction to release the journal but having a portion engaging with the box or its carrier and necessitating movement of 125 said engaging part in a different direction before the cap can be moved out of retaining position, and elastic provision for maintaining said engaging part in engagement, substantially as specified.

3. The combination of the journal-box, 130 bushings receiving said journal and fitting in said box, and a retaining-cap having a portion for closing the box so as to prevent removal of the journal-bushing therefrom, said

cap being movable in one direction to release the journal-bushing but having a portion engaging with the box or its carrier and necessitating movement of said engaging part in a different direction before the cap can be moved out of retaining position, substantially as specified.

4. The combination of the journal-box with a retaining-cap therefor having a portion for closing the box so as to prevent removal of the journal therefrom, said cap being pivoted so as to be movable in one direction out of retaining position but having a portion transverse to the axis of the pivot and engaging with the box or its carrier and necessitating movement of said engaging part in a direction different from that of the swinging movement before the cap can be swung out of retaining position, substantially as specified.

5. The combination of a journal-receiving box with a removable cap therefor having a pivot-stud and a shoulder transverse to the axis of the pivot for engagement with the box whereby a vertical movement of the cap in order to free said shouldered portion is necessary before the cap can be swung around out of its retaining position, substantially as specified.

6. The combination of a journal-receiving box with a removable cap therefor, having a pivot-stem, a plate for closing the end of the box, and a shoulder transverse to the axis of

the pivot for engaging with the top of the box, whereby vertical movement of the cap in order to free the said shouldered portion 35 from the box is necessary before the cap can be swung around out of retaining position, substantially as specified.

7. The combination of the journal-box with a retaining-cap therefor having a pivot-stem 40 and a spring acting to depress the cap, said cap having a shoulder transverse to the axis of the pivot for engagement with the box and necessitating movement of the cap before it can be swung around out of retaining position, and a support for retaining the cap in the elevated position when thus swung around and for exerting such friction upon the cap as to prevent it from being accidentally swung back into retaining position, substan- 45 tially as specified.

In testimony whereof we have signed our names to this specification in the presence of subscribing witnesses.
